SIGNAL CONVERTER CIRCUIT

Dudley E. Foster, Orange, N. J., assignor to
 Radio Corporation of America, a corporation
 of Delaware

Application April 13, 1936, Serial No. 73,998

9 Claims. (Cl. 250—20)

My present invention relates to radio frequency signal converter circuits, and more particularly to converters of the electron coupled type. As is well known, the frequency converter receiver 5 or first detector, of a superheterodyne receiver produces in its output circuit the sum and difference frequencies of the signal and locally produced oscillation frequencies. In addition to these sum and difference frequencies, there are 10 also produced frequencies equal to the sum and difference of integral multiples of the signal and oscillator frequencies. These latter frequencies are usually referred to as higher order effects, since they are due to terms in the expression 15 representing the tube characteristic higher in order than the term which results in the desired operating intermediate frequency. For example, in the simple type of converter tube, wherein the signal and oscillator voltages are simultaneously applied to a common control grid, if the characteristic of the plate current be expressed as a power series, i. e., a series whose successive terms are ascending powers of the grid voltage, then 20 the second order (voltage squared) term results in the desired conversion frequency and higher 25 orders in undesired frequency terms.

The electron coupled type of frequency converter, and its many circuit forms, is well known at the present time. In such a converter the oscillator voltage is applied to one control grid while the signal voltage is applied to another grid, the latter being usually spaced from the former, and both grids being disposed in the electron stream flowing between the cathode and output 30 electrode of the tube. In this type of converter the higher order terms give undesired frequencies, just as in the simple type of converter tube. Only these frequencies falling within the response band of the intermediate frequency network will be 35 transmitted to the second detector, or demodulator. However, any undesired term falling within the intermediate frequency network response band will likewise reach the demodulator, and thus give an undesired response. This difficulty 40 is most commonly encountered when twice the intermediate frequency falls within the signal frequency range it is desired to receive. In this case, the intermediate frequency can result not only from the difference between the signal and oscillator frequencies, but, also, from the difference between twice the signal frequency and the oscillator frequency.

The latter problem can be more clearly understood when viewed in the light of an actual example. Assuming that the operating I. F. is 500

5 k. c., then the oscillator frequency will be 1500 k. c. when the receiver is tuned for reception of a 1000 k. c. signal. If now the oscillator frequency be slightly changed to 1501 k. c., then the resultant I. F. from the first order term will be 501 k. c. 10 The second order term will give a frequency equal to twice the signal frequency, i. e., the difference between 2000 k. c. and 1501 k. c., or 499 k. c. It will, thus, be seen that there will be applied to the second detector two frequencies of 501 k. c. 15 and 499 k. c., with the result that a beat note equal to their difference, 2 k. c., will be heard.

At signal frequencies other than twice the I. F., multiple response will be evidenced instead of audible whistles. Consider again a superheterodyne receiver using a 500 k. c. I. F. with an input signal of 1020 k. c. If the oscillator frequency is 1520 k. c., then the I. F. of 500 k. c. will be obtained. Furthermore, if the oscillator frequency is 1540 k. c., the second order term of the signal 20 grid characteristic will give an output of twice signal frequency minus oscillator frequency, or 2040 k. c., minus 1540 k. c., resulting in 500 k. c. It is seen, therefore, that for any applied signal frequency, there are at least two oscillator frequencies which will result in the correct I. F. 25

Accordingly, it may be stated that it is one of the main objects of my present invention substantially to reduce undesired responses in a converter of the electron coupled type, which responses correspond to terms higher than the first order term in the expression representing the converter tube characteristic; the reduction in undesired responses being accomplished by applying the local oscillator voltage simultaneously 30 to the signal and oscillator grids, but the oscillator voltage being impressed on the two grids in out-of-phase relation, and the magnitude of the out-of-phase oscillator voltage being chosen to 35 secure the substantial reduction of the higher 40 order terms referred to.

Another important object of the present invention is to cancel from the output circuit of an electron coupled type of frequency converter, undesired responses produced by the second order effect, and this cancellation being accomplished by applying the local oscillator voltage simultaneously to the oscillator grid and the signal grid, the oscillator voltage being applied in reversed 45 phase to the respective grids; it being pointed out that since the second order effect is less than the first order effect, the amount of local oscillator voltage on the signal grid which causes 50 cancellation of the second order effect will result 55

in only a slight decrease in the desired first order frequency conversion.

In existing electron discharge tubes of the type employed in electron coupled converters, the amount of local oscillator voltage to be applied to the signal grid for cancellation of undesired responses, is a function of the bias on the signal grid since the tube characteristic with respect to the signal grid is not purely exponential. Hence, it may be stated that it is another object of the present invention to apply local oscillator voltage of an electron coupled converter to the signal and oscillator grids in phase and magnitude relations substantially to reduce the higher order effects resulting in undesired responses in the frequency range it is desired to receive, and yet employ automatic volume control action on the converter; this dual result being secured by utilizing a phase inverter tube to impress local oscillator voltage on the signal grid, and the bias of the inverter tube being varied concurrently with that of the signal grid of the signal converter tube with the result that the proper amount of local oscillator voltage is applied to the signal grid for any value of signal grid bias.

Another object of the invention may be stated to reside in the provision of an electron coupled converter tube which not only has applied to its signal grid a local oscillator voltage in phase and magnitude substantially to eliminate the undesired responses due to the higher order effects, but wherein the direct current voltage of the oscillator and signal grids are varied in dependence upon received signal amplitude variation.

Still other objects of the present invention are to improve generally the efficiency and operating reliability of frequency converters of the electron coupled type, and more especially to provide such converters which are not only durable, reliable and simple in operation, but economically manufactured and assembled in radio receivers of the superheterodyne type.

The novel features which I believe to be characteristic of my invention are set forth in particularity in the appended claims; the invention itself, however, as to both its organization and method of operation will best be understood by reference to the following description taken in connection with the drawings, in which I have indicated diagrammatically several circuit organizations whereby my invention may be carried into effect.

In the drawings:

Fig. 1 is a schematic circuit diagram showing the basic circuit employed in this invention,

Fig. 2 shows a converter network embodying one form of the invention,

Fig. 3 shows an alternative arrangement of the invention,

Fig. 4 illustrates another embodiment of the invention,

Fig. 5 illustrates another converter arrangement,

Fig. 6 shows a converter network embodying still another form of the invention,

Fig. 7 shows a converter network employing the invention, and utilizing automatic volume control,

Fig. 8 shows a modification of the arrangement of Fig. 7.

Referring now to the accompanying drawings, wherein like reference characters in the different figures designate similar circuit elements, there is shown in Fig. 1 a purely schematic representation of the basic principle involved in the pres-

ent invention. The numeral 1 designates a pentagrid converter tube which is well known to those skilled in the art, and is usually designated as a 2A7. The input electrodes of the tube are connected across a tuned signal input circuit 2, the latter circuit being coupled to a source of signal energy. The local oscillator is schematically represented by the numeral 3, and is connected between the first grid and the grounded side of the cathode bias resistor 4, the latter being shunted by the usual by-pass condenser 5. The fourth grid 6 is connected to the high alternating potential side of the input circuit 2, and the signal grid 6 and oscillator grid 7 have disposed between them a pair of positively biased grids. A positively biased grid is also disposed between the output plate electrode 8 and the signal grid 6.

The numeral 9 denotes the usual variable tuning condenser disposed in the input circuit 2, and the condenser 9 is to be understood as being adjustable over a relatively wide frequency range, as for example the broadcast range of 500 to 1500 k. c. Of course, the tuning range of circuit 2 may be in the higher frequencies, and it is to be clearly understood that the local oscillator circuit 3 is simultaneously tunable, by means of its own tuning element, over a frequency range which differs from the signal frequency range by the operating I. F. The I. F. network is disposed in the circuit connected to the plate 8.

It is not believed necessary to go into the details of the functioning of the converter tube 1. Those skilled in the art are fully aware of the fact that there is produced in the circuit connected to the output electrode 8, the sum and difference frequencies between the applied signal frequency and the local oscillator frequency, as well as frequencies equal to the sum and difference of integral multiples of the signal and oscillator frequencies. The electron stream flowing between the cathode and plate 8 is modulated at the frequencies of the signal and oscillator voltages, and the various modulation frequencies, as explained above, are produced in the circuit connected to the plate 8. The I. F. network being resonated to the desired operating I. F., only those frequencies falling within the response band of the I. F. network will be transmitted to the demodulator.

However, undesired responses produced by the second, third or higher order effects will likewise reach the demodulator, and give undesired responses if any undesired term falls within the I. F. network response band. To reduce substantially these undesired responses there is impressed upon the signal grid 6 a portion of the locally produced oscillator voltage, and this impression is made through the impedance Z. The impedance Z is designed to provide the proper phase so as to produce reduction of the higher order effects.

The impedance Z may be inductive or capacitative; the various following figures illustrate the impedance in these two aspects. The impedance Z must be chosen of such phase and magnitude as to cancel out the response due to the second order term. If the third, or higher, order effect results in undesired responses in the desired frequency range, then the amount of out-of-phase oscillator voltage applied to the signal grid 6, through impedance Z, is adjusted to cancel higher order responses.

In Fig. 2, there is shown a converter network

wherein the out-of-phase oscillator voltage is applied to the signal grid 6 of the converter tube 1 (of the 2A7 type) through condenser 10. The latter is made adjustable so that it can be varied in magnitude to the point where the undesired responses in I. F. network 11 can be cancelled. The condenser 10 is connected between the grid 6 and the high alternating potential side of the tunable oscillation circuit 2' of the local oscillator. The dotted line 12 denotes the usual mechanical coupling between the rotors of the variable tuner condensers 9 and 9'. It is to be clearly understood that the coupling between the oscillator grid 7 and the oscillator is conventional. 15 Further, the tuner circuits may be of the multi-range type, if desired.

The circuit arrangement shown in Fig. 3 embodies a form of the invention wherein the signal grid 6, disposed adjacent the cathode of the converter tube 1, is connected to the plate of the oscillator tube 3' through condenser 10. The oscillator is of a conventional form, and needs no detailed description. The oscillator grid 7, disposed in the positive shielding field, is connected 20 to the grid of the oscillator tube. The condenser 10 may be adjusted to balance out the second harmonic effects in the I. F. output network 11.

The circuit arrangement of Fig. 4 differs from the preceding arrangement in the harmonic cancellation coupling between the local oscillator and the signal grid 6. This coupling comprises the mutual inductance M provided between coil 13 and tunable circuit coil 14. The magnitude of M may be varied until the undesired second harmonic response in network 11 is cancelled out.

With the oscillator higher in frequency than the signal, the signal circuit appears capacitive to the oscillator frequency. If the signal circuit were a pure capacity, then the feedback coupling 40 and signal tank circuit would act as a simple capacitive voltage divider. However, the tank circuit appears as capacity and resistance, so for phase as well as magnitude balance the feedback circuit should comprise resistance, which may be in series or parallel with the feedback capacity. In practice, appreciable reduction is secured 45 without phase balance, but better reduction of spurious components will result from phase as well as magnitude adjustment. Similarly a 50 resistance in conjunction with M would produce better balance by adjustment of phase as well as magnitude. Capacitive and inductive couplings are shown to indicate alternative arrangements.

The modification shown in Fig. 5 involves the 55 connection of the signal grid 6 to the high alternating potential side of signal input circuit 2. The local oscillations are impressed on the signal grid 6 by connecting the low alternating potential side of oscillation circuit coil 15 to the low alternating potential side of signal circuit coil 14 through adjustable condenser 10. The junction 60 of condenser 10 and coil 14 is grounded through condenser 16. The oscillator grid 7 is connected to the high alternating potential side of oscillator circuit 2'. Coil 15 of Fig. 5, padding condensers 10 and 16 and the variable condensers connected to coil 15 represent the tank circuit of a separate oscillator tube. The common coupling to the signal circuit is condenser 16. Condenser 16 is the cancellation coupling condenser; condenser 10 is added in series therewith, the series combination of condensers 16 and 10 acting as an oscillator padding condenser. Adjustment of 10 affects padding, but does not affect 70 the coupling magnitude to signal network.

In the circuit arrangement of Fig. 6, the converter tube 1 is of the type shown in Fig. 2. Otherwise, the arrangement is a variation of that shown in Fig. 4. Here the local oscillator has its normal coupling to oscillator grid 7 through condenser C1; the latter being connected to the high alternating side of oscillator circuit 2'. The harmonic cancellation coupling in this case comprises the mutual inductance M1 provided between cathode coil 17 and the coil of the tunable 10 oscillator circuit 2'. In a practical embodiment of this arrangement it was necessary to decrease the magnitude of condenser C1 to cut down the normal oscillator injection. With this adjustment a decrease of approximately 20 db. in the 15 second order effect was obtained upon proper proportioning of M1.

When AVC action is applied to the converter tube the second harmonic cancellation is affected. This arises by virtue of the fact that the signal 20 grid characteristic is not purely exponential in existing tubes. The amount of oscillator voltage to be applied to the signal grid for harmonic cancellation is a function of the bias on the signal grid. Since the signal grid bias varies in magnitude when AVC is used, it follows that the harmonic cancellation voltage will also vary. It, therefore, becomes necessary to employ a device 25 for insuring the application of the proper amount of oscillator voltage for any signal grid bias. 30

Fig. 7 shows one arrangement for automatically correlating the harmonic cancellation voltage with the converter signal bias value. The local oscillator applies the oscillations to the oscillator grid 7 through condenser C2. The AVC network 35 20, of conventional type, automatically regulates the conversion gain of tube 1. The AVC network, in general, may embody a signal rectifier supplied with I. F. energy, and which rectifier furnishes the direct current voltage component for automatically regulating the signal grid bias of the converter tube 1. Of course, the AVC network 40 may also regulate any of the high frequency signal transmission tubes in gain. Furthermore, the AVC rectifier may be an independent rectifier, or 45 may be part of the demodulator of the system, and in the latter case the direct current voltage component of detected I. F. voltage would be used for the AVC action.

The harmonic cancellation oscillator voltage is 50 applied to the signal grid 6 through a phase inverter tube 21. The electron discharge tube 21 has its plate connected to the high alternating potential side of signal circuit 2 through a condenser C3, the plate being supplied with proper 55 positive voltage through the choke 22. The control grid of the inverter tube 21 is connected to the high alternating potential side of the local oscillator circuit 2' through condenser C4, and the cathode of the inverter tube is grounded through 60 bias network 24.

When bias increases on tube 1, the bias decreases 65 on tube 21. By taking screen voltage for tube 1 through resistors 25 and 26, as tube 1 is biased negatively the screen potential increases in a positive direction, and with it, to a lesser degree, the potential of point 27 of resistor 26. By connecting the control grid of tube 21, through resistor 23, to point 27, the grid potential of tube 70 21 becomes less negative when that of tube 1 becomes more negative. Resistor 24' in the cathode of 21 is required so that the cathode of tube 21 is at greater positive potential, relative to ground, than point 27; the grid of tube 21 thus being 75

maintained negative with respect to its own cathode.

In this way a change in gain control bias on the signal grid 6 will automatically vary the bias on the grid of the inverter tube 21, and the gain of the latter will be varied. The function of the tube 21 is to invert the phase of the applied local oscillator voltage so as to secure the proper harmonic cancellation phase. The variation in gain of tube 21 is chosen so that the proper amount of oscillation voltage is applied for every change in converter signal grid bias. In this way the departure of the converter signal grid characteristic from the pure exponential type is compensated for; the compensation involves the automatic correlation of the magnitude of the applied harmonic cancellation oscillator voltage with the value of the converter signal grid bias.

At the expense of some conversion sensitivity the phase inverter tube 21 may be dispensed with. The local oscillator, conventionally represented in Fig. 8, is shown coupled, through condensers, to the local oscillator grid 7 and the signal grid 6. The AVC connections, from the usual AVC network, are made to the signal and oscillator grids. The bias of the oscillator grid is automatically varied with that of the signal grid in this modification. This requires that the oscillator grid 7 draw little current for practical AVC action, and it must, therefore, be run negative. Both grids vary in the same polarity sense, but at different rates. In general, grid 6 varies less than grid 7.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In an electron discharge tube which is provided with at least a cathode, an output electrode and an electron path therebetween, the method which includes drawing electrons to an intermediate point in said path, retarding said electrons to form a virtual cathode which is beyond said point, modulating the density of the virtual cathode by varying the attraction of said electrons through attracting the part of said electrons from said virtual cathode to said output electrode, causing a received signal to vary the further attraction of said part of the electrons, the modulation of the density of the virtual cathode thereby causing modulation of the signal in said tube, and simultaneously modulating said part of the electrons in out-of-phase relation with said first modulation and to an extent such as to reduce substantially the appearance of second order, or higher, term effects.

2. In a superheterodyne receiver, a first detector system comprising a tube having a cathode and an oscillation electrode near said cathode, means electrically connected with said oscillation electrode for varying the alternating current voltage thereof at a predetermined locally produced oscillation frequency, said tube including a control grid and an anode located in the space path beyond said oscillation electrode, a source of signal voltage coupled between said control grid and said cathode, and additional means connected between said control grid and said first means for impressing upon said control grid said locally produced oscillations in phase and magni-

tude such that undesired responses due to the second order, or higher, term of the detection characteristic are substantially reduced.

3. In a superheterodyne receiver, a first detector system comprising a tube having a cathode and an oscillation electrode, means electrically connected with said oscillation electrode for varying the alternating current voltage thereof at a predetermined locally produced oscillation frequency, said tube including a control grid and an anode, said control grid being located in the space path between the cathode and said oscillation electrode, a source of signal voltage coupled between said control grid and said cathode, and additional means connected between said control grid and said first means for impressing upon said control grid said locally produced oscillations in phase and magnitude such that undesired responses due to the second order, or higher, term of the detection characteristic are substantially reduced, means for developing a bias control voltage which automatically varies with the intensity of said signal source, means for applying said bias voltage to said control grid, and additional means, responsive to the variation in said bias control voltage, for automatically correlating the local oscillation voltage impressed on said control grid with the change in said bias control voltage.

4. In combination in a first detector network of a superheterodyne receiver, an electron discharge tube provided with at least a cathode, an output electrode, a pair of control electrodes disposed between the cathode and output electrode, and means electrostatically shielding said pair of control electrodes, a tuned signal input circuit connected between the cathode and one of the control electrodes, means coupled to the cathode and the other control electrode for varying the alternating current voltage of said other control electrode at a frequency rate which differs from the signal frequency by a predetermined intermediate frequency, and means coupling said input circuit and said varying means for impressing on said first control electrode alternating current voltage varying in frequency at said oscillation frequency rate, the phase of the alternating current voltage impressed on said first control electrode being related to the phase of the voltage on said other control electrode substantially to reduce the effect of the second order term of the detection characteristic on the electron stream flowing between the cathode and said output electrode.

5. In a first detector network of a superheterodyne receiver, an electron discharge tube which includes a cathode, an anode and at least two control grids disposed in the electron stream between the cathode and anode, a resonant network in the anode circuit which is tuned to an operating intermediate frequency, a tunable signal input circuit connected between the cathode and one of the control grids, a source of local oscillations, variable over a predetermined local oscillator frequency range, coupled between the cathode and the other control grid, and means, electrically connected with said local oscillation source and the said signal input circuit, for impressing upon said first control grid local oscillator voltage which is out-of-phase with the oscillator voltage impressed on the other control grid.

6. In a first detector network of a superheterodyne receiver, an electron discharge tube which includes a cathode, an anode and at least two control grids disposed in the electron stream

- between the cathode and anode, a resonant network in the anode circuit which is tuned to an operating intermediate frequency, a tunable signal input circuit connected between the cathode 5 and one of the control grids, a source of local oscillations, variable over a predetermined local oscillator frequency range, coupled between the cathode and the other control grid, and means, electrically connected with said local oscillation 10 source and the said signal input circuit, for impressing upon said first control grid local oscillator voltage which is out-of-phase with the oscillator voltage impressed on the other control grid, means, responsive to variations in signal amplitude, 15 for automatically regulating the first control grid bias, and additional means responsive to said last named means for varying the magnitude of the oscillator voltage impressed on said first control grid.
- 20 7. A frequency converter tube comprising a cathode, an anode and at least two additional electrodes disposed in succession in the electron stream between the cathode and anode, a source of oscillations connected to one of the said electrodes to vary the potential thereof at a predetermined frequency, a source of signals connected to the other electrode to vary the voltage thereof at a frequency different from the oscillation frequency, a circuit connected to the anode to utilize the frequency component of anode current equal to the difference between said signal and oscillation frequencies, a high frequency coupling path, 25 independent of said electron stream, between said electrodes, said path including a reactive impedance whose magnitude and phase are chosen so that said oscillations are impressed on said signal electrode in out-of-phase relation with the 30 oscillations impressed on said one electrode thereby to prevent the production of harmonic responses in said anode circuit, and means, responsive to signal amplitude changes, to vary the gain of said converter tube.
- 20 8. In a first detector network of a superheterodyne receiver, an electron discharge tube which includes a cathode, an anode and at least two control grids disposed in the electron stream between the cathode and anode, a resonant network in the anode circuit which is tuned to an operating intermediate frequency, a tunable signal input circuit connected between the cathode 25 and one of the control grids, a source of local oscillations, variable over a predetermined local oscillator frequency range, coupled between the cathode and the other control grid, and means electrically connected with said local oscillation source and the said signal input circuit, for impressing upon said first control grid local oscillator voltage which is out-of-phase with the oscillator voltage impressed on the other control grid, means responsive to signal amplitude variation for controlling the potential of said one grid, and additional means responsive to said signal 30 amplitude variation for controlling the magnitude of said out-of-phase voltage.
- 35 9. In a first detector network of a superheterodyne receiver, an electron discharge tube which includes a cathode, an anode and at least two control grids disposed in the electron stream between the cathode and anode, a resonant network in the anode circuit which is tuned to an operating intermediate frequency, a tunable signal input circuit connected between the cathode 40 and one of the control grids, a source of local oscillations, variable over a predetermined local oscillator frequency range, coupled between the cathode and the other control grid, and means electrically connected with said local oscillation source and the said signal input circuit, for impressing upon said first control grid local oscillator voltage which is out-of-phase with the oscillator voltage impressed on the other control grid, means responsive to signal amplitude variation for controlling the potential of said one grid, and additional means responsive to said signal amplitude variation for controlling the magnitude of said out-of-phase voltage.
